UNITED STATES PATENT OFFICE.

PAUL G. STROUD, OF BELMONT, AND WALTER A. SIMOND, OF FRANKLIN, NEW HAMPSHIRE, ASSIGNORS TO ACME KNITTING MACHINE & NEEDLE COMPANY, OF FRANKLIN, NEW HAMPSHIRE, A CORPORATION OF NEW HAMPSHIRE.

KNITTING MACHINE.

Application filed November 4, 1922. Serial No. 599,024.

This invention relates to knitting machines, and more particularly to hosiery knitting machines. The invention is especially concerned with that type of machines 5 for knitting hosiery which is adapted to fashion the heel and toe of a stocking and to knit either plain or ribbed fabric, so that a complete stocking having a plain foot and a ribbed leg can be produced automatically 10 in such a machine.

In machines of this type where it is desired to have the ribbed portion of the leg begin immediately above the heel, much difficulty is experienced due to the fact that 15 the presence of the heel pocket in the knitted web of fabric reduces the tension transmitted from the takeup through the fabric to the group of needles acting immediately above the pocket. The fact that a greater 20 tension is exerted on certain needles than on others naturally results in producing imperfect work, and frequently the decrease in tension due to this cause is sufficient to prevent the proper casting of the stitches 25 from those needles subjected to the reduced tension. It has been proposed to overcome this difficulty through the use of supplemental tensions or takeups designed to act locally on the fabric to pull out the slack 30 that is introduced in the knitted web by the heel or toe pocket; but these mechanisms obviously complicate the machine, particularly since they must be thrown into and out of operation by some automatic arrangement.

It is the chief object of the present invention to devise a simpler and more practical solution for this problem. The invention aims especially to avoid the use of supplemental takeups or tensions and to maintain a uniform tension on the loops held by the entire series of needles through the action of a main web takeup.

The nature of the invention will be readily understood from the following description when read in connection with the accompanying drawings, and the novel features will be particularly pointed out in the appended claims.

Referring now to the drawings,

Figure 1 is a vertical cross sectional view through the needle cylinder and web guide of a hosiery knitting machine of the char-

acter above described, showing this machine equipped with a mechanism embodying the 55 present invention;

Fig. 2 is a perspective view of the takeup mechanism forming a part of the machine shown in Fig. 1; and

Fig. 3 is a front view of certain details 60 of the actuating mechanism for the takeup rolls shown in Fig. 2.

The invention is herein illustrated as applied to the machine shown and described in application Serial No. 293,113 filed April 28, 1919, and assigned to the assignee of the 65 present invention.

Referring first to Fig. 1, 2 designates a stationary needle cylinder mounted on the upper end of a web guide 3 and supporting 70 a circular series of needles 4. These needles are operated by suitable cams mounted on a revolving table or cam ring 5 which is driven by a bevel gear 6 secured fast on a shaft 7. Cooperating with the vertical cylinder needles 4 is a set of horizontal needles 8 supported in a stationary dial 9 and arranged to be operated by suitable cams. The machine also includes suitable pattern 75 mechanism and connections operated thereby for controlling and operating the needles so that the machine will automatically knit a stocking having, say, a plain foot with heel and toe pouches and a ribbed leg. The cylinder needles operate alone in knitting plain work, but the dial needles cooperate with the cylinder needles in knitting ribbed work. The general operation of the machine will be evident to those skilled in this 80 art, but reference should be made to the application above designated for a thorough understanding of the construction and operation of the machine shown in this figure. Another machine of this general type is 85 shown in Patent No. 1,282,880, granted October 29, 1918.

It is customary to use a web takeup in a machine of this type for the purpose of gripping the knitted web of fabric F at a point located relatively remote from the 100 needles and feeding this web downwardly, thus maintaining the proper tension on the web to facilitate the casting of the loops of yarn from the needles as the knitting operation progresses. So long as a tubular 105 fabric of substantially uniform dimensions

is being produced, there is no difficulty in maintaining the tension on the loops substantially uniform at all points circumferentially of the circular series of needles. 5 But when a heel pocket has been formed and descends from the verge of the needles, the loose or slack fabric constituting the pocket does not transmit the tension of the takeup mechanism to those needles located immediately above the pocket; and this unequal distribution of tension on the needles and on the loops of yarn held thereby produces imperfect work. This action is not especially troublesome if the machine continues to knit plain fabric, but it is very objectionable when the machine changes from plain to ribbed knitting at a point immediately above the heel. The present invention provides a mechanism which obviates this difficulty and maintains a substantially uniform tension on the needles throughout the knitting operation, notwithstanding the presence of the heel or toe pockets. 15

25 The mechanism shown comprises a web takeup including two rolls 12 and 14, respectively, the ends of which are supported in the opposite walls of a cylinder 15. The bearings for the roll 12 are fixed with reference to the cylinder 15, but the roll 14 is mounted to yield bodily toward and from the roll 12, being spring pressed toward the latter roll, as is common in mechanisms of this character. The takeup cylinder 15 has 30 a flanged head 16 which is rotatably supported in a bracket 17 bolted to the machine frame. A ring 18 overlies the flange 16 and holds the cylinder in the bracket. Formed on the outer edge of the flange 17 are teeth which mesh with a worm 20 fast on a horizontal shaft 21 supported in suitable bearings. A pulley 22 is secured to this shaft and is belted to any convenient source of power in the machine. These parts thus 35 rotate the entire takeup mechanism in a horizontal plane.

40 For the purpose of rotating the rolls 12 and 14 about their axes, a ratchet wheel 24 is secured to the shaft 25 of the roll 12, and a bell crank lever 26 is mounted on this shaft immediately behind the ratchet 24. This lever carries a pin or roll 27 which runs in contact with the lower wavy edge 28 of the bracket 17, the pin being held in contact 45 with said edge by a spiral spring 29, one end of which is secured to a pin 30 projecting from the lever 26, while the other end is secured to a stationary arm 31 fastened to the cylinder 15.

50 It will thus be evident that as the cylinder 15 is revolved about its axis by the worm 20, the lever 26 will be oscillated about the shaft 25. A pawl 32 pivoted on the lever 26 is held in engagement with the teeth 55 of the ratchet 24 by means of a spring 33.

Consequently, as this pawl moves up and down due to the oscillations of the lever 26, it rotates the ratchet wheel 24, and with it, the roll 12. Another pawl 34 engaging the opposite side of the ratchet wheel 24 prevents any retrograde movement of this wheel. The two rolls 12 and 14 are geared together at their ends opposite the ratchet 24, one of the gears being shown at 35 in Fig. 1, so that they are compelled to rotate 70 in unison but in opposite directions. 75

This general construction of a takeup mechanism is already known and no novelty 80 is claimed here.

85 It will now be evident that while the knitting operation is progressing, the web F of fabric will be fed downwardly by the rolls 12 and 14 in the usual manner. At the same time, this web of fabric will be twisted due to the bodily rotation of the takeup mechanism. This twisting of the fabric distributes the strain uniformly on the entire series of loops held by the needles notwithstanding the presence of heel or toe 90 pockets in the web. It effectually overcomes, therefore, the difficulties which otherwise would be introduced in the knitting operation due to the presence of the heel or toe pockets. The twist in the fabric is subsequently taken out in the laundering and pressing of the hosiery. The rate of rotation of the takeup mechanism and of the rolls 12 and 14 is so proportioned to the rate at which the goods are produced as to 95 maintain the desired tension on the needles.

100 This invention therefore provides a mechanism which avoids entirely the use of supplemental takeups or tension devices. It is extremely simple in construction, is economical to manufacture, and requires no attention other than that required by the usual web takeups. The fact that it is unnecessary to use any automatic mechanism for throwing it into or out of action, as is required when supplemental takeup mechanisms are used, is an important advantage 105 from both the manufacturing and operating standpoints.

110 While we have herein shown and described the best embodiment of our invention which we have so far devised, it will be appreciated that the invention is not limited to embodiment in the specific form shown.

115 Having thus described our invention, what we desire to claim as new is:

1. In a circular knitting machine, the combination with knitting instrumentalities including a circular series of needles, of means operative during circular knitting to twist and simultaneously tension the knitted web of fabric. 125

2. In a circular knitting machine, the combination with knitting instrumentalities including a circular series of needles, of means 130

for acting on the knitted web of fabric during circular knitting to twist and simultaneously feed said web of fabric.

3. In a circular knitting machine, the combination with knitting instrumentalities including a circular series of needles, of means for operating substantially continuously on the web of knitted fabric to feed and twist the web simultaneously to maintain a substantially constant tension on the fabric at the needles.

4. In a circular knitting machine, the combination with knitting instrumentalities including a circular series of needles, of a takeup for the web of knitted fabric, and mechanism for relatively rotating said needles and takeup during circular knitting to twist said web of fabric.

5. In a knitting machine, the combination with knitting instrumentalities including a stationary needle cylinder and a circular

series of needles supported thereby, of a takeup comprising rolls between which the web of fabric is fed, means for rotating said rolls, and mechanism for bodily rotating said takeup to twist the web of fabric.

6. In a circular hosiery knitting machine, the combination with knitting instrumentalities including needles and operating mechanism therefor for causing them to knit either plain or ribbed fabric and to change automatically from one style of knitting to the other, of a takeup for the web of knitted fabric, and mechanism for relatively rotating said needles and said takeup during circular knitting to twist the portion of said web of fabric between the takeup and said needles.

In testimony whereof we have hereunto signed our names to this specification.

PAUL G. STROUD.

WALTER A. SIMOND.
